UNITED STATES PATENT OFFICE.

GODFREY STIBBE, OF LEICESTER, ENGLAND.

KNITTED GLOVE AND METHOD OF PRODUCING THE SAME.

1,346,517.

Specification of Letters Patent. Patented July 13, 1920.

Original application filed August 8, 1916, Serial No. 113,728. Divided and this application filed March 12, 1920. Serial No. 365,310.

To all whom it may concern:

Be it known that I, GODFREY STIBBE, subject of the King of Great Britain, residing at Leicester, in the county of Leicester, England, have invented certain new and useful Improvements in or Relating to Knitted Gloves and Methods of Producing the Same, of which the following is a specification, reference being had therein to the accompanying drawing.

This invention relates to knitted gloves and to the method of producing the same and has for its object to produce an improved machine made glove one of the advantages of the process forming the invention being that articles of the character concerned can be made much more quickly and cheaper than heretofore.

By the process of manufacture herein to be described, the main portions of the glove i. e. wrist, hand, thumb and fingers may be made on the same machine, thus obviating the customary pressing-off and running on operations.

25 In carrying out the process, a circular knitting machine is employed for preference, although it may be possible to make use of the same method on a flat knitting frame or straight bar machine.

30 A machine knitted glove according to this invention comprises a seamless wrist and hand, a thumb and a series of fingers knitted in the flat and with selvaged edges as a jointless continuation of the hand.

35 The essence of the invention is the formation of the finger portions as jointless continuations or extensions of the hand portion i. e. without a seam or joint at the base or root of the fingers where the circular fabric is merged into the separated finger portions.

40 In the improved glove the two outside fingers may be seamed down the inner side only and the two inside fingers seamed down each side.

45 In a modified form of the glove all the fingers may be seamed down each side; further, in such glove the fingers may be formed with seamless extremities.

50 The thumb of the improved glove may be finished with a single seam, or it may have seams upon two opposite sides in which latter case it may also have a seamless extremity.

55 It is also a feature of the invention that in a glove characterized by the aforesaid features, the aggregate loops in the courses

of the combined fingers is greater than the number of loops in the courses of the hand portion.

In describing the invention reference will be made to the accompanying drawings wherein:

Figure 1 is a flat view of the complete glove formed according to this invention.

Fig. 2 is a perspective view of the same.

Fig. 3 is a perspective view showing an alternative form of the improved glove.

Fig. 4 is a perspective diagrammatical view of a blank partly formed and showing the thumb portion.

Fig. 5 is a similar view showing a further stage in the process the blank having the finger portions formed thereon.

Fig. 6 is a further similar view showing a blank having finger portions formed according to an alternative method.

Fig. 7 shows the blank of Fig. 6 carried a stage farther in the process.

Fig. 8 is a diagram of the needle circle and is hereinafter referred to in explaining the method of obtaining a greater number of loops in the courses of the combined fingers than there are in the courses of the hand portion of the glove.

Fig. 9 illustrates a detail in the finish of the finger extremities.

Figs. 4, 5, 6, 7 and 9 are drawn to a smaller scale than Figs. 1, 2, 3 and 8, and throughout the drawings like parts are designated by the same reference characters.

The improved glove shown in Figs. 1 and 2 has a wrist and hand portion 1 of circular fabric seamlessly combined with a thumb 2 and fingers 3, 4, 5 and 6, the outside fingers 3 and 6 being seamed at 7 down the inner side only and the two inside fingers 4, 5 being seamed at 8 down each side.

The glove shown in Fig. 3 has a wrist and hand portion 1 of circular fabric seamlessly combined with thumb and fingers 100 similarly to the glove shown in Fig. 1, except that in this alternative form all the fingers are seamed at 9 down each side and at the extremities 10 are without seams.

The thumb 2 may have a seam 11 down each side as shown in Figs. 2 and 3, or it may, as will be hereinafter described, be formed with a single seam. When seamed upon two sides it may be without a seam at the tip 12 as shown in Fig. 3, or the extremity may be closed in the manner shown in Fig. 2.

The method—subject to modifications hereinafter mentioned—consists in first knitting a piece of circular fabric to form the wrist and part of the hand portion 1 5 (Fig. 4) up to the root of the thumb, after which knitting proceeds upon a certain number of the needles while the others remain out of action, the length of fabric formed by the said needles which continue in action 10 constituting what may be termed the thumb fabric 2^a. The number of needles which continue in action to form the said thumb fabric and the duration of their operation will, of course, depend upon the desired 15 width and length of such fabric.

After the formation of the thumb fabric 2^a knitting again proceeds upon all the needles and circular fabric is produced to complete the hand portion 1 of the glove 20 up to the base or root of the fingers. The length of thumb fabric 2^a is now found to be seamlessly united at each end with the fabric 1 constituting the hand portion. After completing the hand portion, knitting 25 is continued upon certain individual sets of the needles to produce lengths of fabric 3^a, 4^a, 4^b, 5^a, 5^b and 6^a, (Fig. 5) to constitute finger fabrics. For instance, certain needles may continue in action while the others are 30 inactive the operating needles producing the fabric portion 3^a or 6^a to form one of the outside fingers *i. e.* either the first or fourth finger of the glove. The fabrics 3^a and 6^a may be made at different times or both at 35 the same time, the needles producing same going out of action when the parts are finished, after which certain other needles come into action and knit a length of fabric to constitute one half of the next finger *i. e.* 40 either the inside 4^a, 5^a or outside 4^b, 5^b, of the second or third fingers, this process being repeated to separately produce the said lengths of fabric to constitute the requisite half portions for the second and third 45 fingers, it being arranged that the inside halves 4^a, 5^a and outside halves 4^b, 5^b of the said second and third fingers shall be appropriately positioned upon opposite sides of the circular hand fabric 1 to come together 50 and have their respective edges 4^c, 4^d and 5^c, 5^d joined to form the complete fingers.

In an article or blank thus produced (Fig. 5) the thumb fabric 2^a and finger fabrics 3^a, 4^a, 4^b, 5^a, 5^b, 6^a, are seamlessly united with 55 the main fabric 1, each separately formed length has a selvage at each edge, the thumb, first finger and fourth finger are formed whole and the second and third fingers are formed in halves. Briefly stated therefore 60 the process may be said to consist in forming on the same machine a circular wrist and hand portion having integral therewith a whole thumb fabric, whole outside finger fabrics, and half inside finger fabrics.

65 To obtain the necessary width of fabric

for the fingers, the finger fabrics or lengths may be formed in such a manner that they overlap one another at the base as shown in Fig. 5 and thus provide the additional material necessary at the base or root to 70 form a gusset between the fingers.

This overlapping may be effected by employing for the knitting of a finger portion some of the needles upon which the previous or adjacent finger portion was or is to be 75 formed; thus by using some needles twice for producing adjacent finger fabrics the number of loops in the circular course or courses of the glove in the region of the roots of the fingers can be made to exceed 80 the maximum number of needles in the machine and consequently exceed also the maximum number of loops in the circular courses of the hand portion of the glove so that the additional material requisite for the fingers 85 is provided. This will be hereinafter fully explained.

The process already described, may admit of variation as regards the formation of the finger portions, that is to say, it may be 90 immaterial as to whether one finger portion is formed before another or whether the said finger fabrics shall be formed at different times or two or more of them at the same time. Obviously it may be an advantage to proceed with the finger formation in a circular order commencing say with the finger fabric 3^a for the first finger, then forming the fabric 4^a for the inside half of the second finger, next the fabric 5^a for the 100 inside half of the third finger, then the fabric 6^a for the fourth finger followed by the fabric 5^b for the outside half of the third finger, and lastly the fabric 4^b for the outside half of the second finger. Or this 105 order might be reversed. Or again finger fabrics may be formed simultaneously upon opposite sides of the circular hand portion. For example, the first and fourth finger fabrics 3^a and 6^a may be formed at the same 110 time as also may be the separate halves 4^a, 4^b of the second finger and the halves 5^a, 5^b of third finger; or the front half of one *e. g.* 4^a and the back half 5^b of the other of these fingers may be formed and then the halves 115 5^a and 4^b.

To facilitate the clear comprehension of the improved process, a specific example of the production of a glove blank upon a circular knitting machine, the cylinder of 120 which is equipped with 160 needles, will now be described, it being understood that the numbers of needles referred to are not binding but are given merely as an illustration.

The glove is commenced by knitting upon 125 the full complement of needles a length of circular fabric.

The thumb fabric is knitted upon 58 needles while the rest remain quiescent. Then the circular knitting is continued on 130

all needles. The finger fabrics are next knitted each upon a separate group of needles which for purpose of description will be designated (a), (b), and so on and 5 are illustrated in Fig. 8. The various groups will be referred to in circular order around the circle of needles the finger fabrics concerned being shown in Fig. 5. The first finger fabric is formed upon a group of 10 needles *a* comprising 46 in number. The front half of the second finger (fabric 4^a) is formed upon a group *b* of needles 26 in number and of which 6 belong to group *a*. The front half of the third finger (fabric 15 5^a) is made upon a group of needles *c* 22 in number and of which 6 belong to group *b*. The needles (42 in number) of the next group *d* produce the fourth finger fabric 6^a. The back half of the third finger (fabric 20 5^b) is made upon a group *e* composed of 22 needles 6 of which belong to group *d*, and the back half of the second finger (fabric 4^b) is made upon a group *f* composed of 26 needles 6 of which belong to group *e*. Thus 25 while there are but 160 needles in the cylinder, 184 loops are formed in the circumference of the glove by reason of the overlapping or double use of some of the needles as shown at the points *g*, *h*, *i*, *j*. Conveniently the groups may operate simultaneously in pairs thus *a* and *d*, *b* and *e*, and 30 *c* and *f*, or they may operate individually. It is an important advantage in connection with the method involved in this invention that the edges of the thumb and 35 finger fabrics are selvged as this greatly facilitates the joining up of such parts and enables a neater seam to be formed than is possible when the edges are raw, besides 40 obviating the possibility of fraying or running back.

In finishing the glove the first and fourth fingers are completed by seaming together the edges 3^b, 3^c and 6^b 6^c of the finger fabrics, 45 the second and third fingers are completed by bringing together the half finger portions on opposite sides of the glove and joining them down each side, the lengths of fabric for the first and fourth fingers are 50 preferably so disposed on the hand portion, that when they are folded or doubled lengthwise and seamed the seamed edges will be situated upon the inside of the fingers *i. e.* between such fingers and the next there- 55 by making such fingers and the entire glove seamless on the outside.

According to the modified method illustrated in Figs. 6 and 7 the hand portion 1 and the thumb fabric 2^a are made in the 60 manner already described but the finger portions are made in a continuous manner from one side only of the tubular hand portion 1.

The finger portions may extend from the 65 front or back of the hand portion but prefer-

ably they are integrally united with the back as shown in Fig. 6 and comprise a length of fabric 13 for the first finger, a piece 14 for the second finger a piece 15 for the third finger and a piece 16 for the fourth finger. 70 These finger fabrics are made twice the length of the fingers and are knitted in extension from the hand portion in the manner already described as regards the overlapping parts at the base of the fingers. 75

In completing the glove according to this method, the finger fabrics—each cut or made in the proper length—are doubled or folded over in the manner shown in Fig. 7, their ends are joined to the edge 17 of the opposite side of the hand portion 1, and then the opposing halves of each doubled or folded finger portion are joined together down the sides as shown at 9 in Fig. 3. This method produces fingers which are seamless at the 80 extremity 10 seeing that the fold 10^a (Fig. 7) in each continuous finger portion ultimately forms the tip. 85

By forming the finger extensions on the back part of the hand portion the joint of 90 the ends of such finger portions to the hand part will be situated on the inside of the glove at the locality 17^a (Fig. 7) and will therefore be less conspicuous.

In joining the turned over ends of the 95 finger portions to the edge 17 of the hand portion the said ends may slightly overlap one another as shown in Fig. 7 to give the desired fullness at the base of the fingers, and the joining up may be effected by linking or seaming the parts together or in any other convenient manner. 100

To obviate a square formation at the tips of the finger formed by the fold 10^a in the finger portions, the sides of the latter may 105 be trimmed off near the folded part (as indicated by the dotted lines in Fig. 9) before or after the edges have been seamed or otherwise joined together. Alternatively the finger portions may be fashioned during knitting for the same purpose. 110

Instead of making all the fingers by the method illustrated in Figs. 6 and 7 some of them *e. g.* the outside fingers 3 and 6 may be made in the manner described with reference to Figs. 2 and 5. 115

The thumb admits of being completed in several ways. For instance the side edges of the loop of fabric 2^a may be joined in which case a thumb of the kind shown in Fig. 3 is produced the tip 12 being seamless. The folded part 12^a of the fabric 2^a which forms the seamless tip may be trimmed in the manner previously described with reference to Fig. 9 to avoid a square end. Another method is to cut the loop 2^a through at the fold 12^a and after shaping the opposing halves join them together along their edges. This makes a thumb of the kind shown in Fig. 2. A further method is to 125 130

make the thumb fabric extra wide and sever the inner end of the loop at the point 2° from the hand portion 1 thus producing a thumb fabric of the same character as the 5 finger fabrics 3^a and 6^a (Fig. 5). The thumb is completed by joining together the longitudinal side edges, closing the tip or end and securing the said edges at the base to the 10 part of the hand portion from which the loop termination was severed. A thumb thus produced will have a single seam situated down the inside.

The improved glove may or may not be provided with a rib top *i. e.* a ribbed wrist 15 portion (not shown) but when it is to have this the said ribbed portion may be run on in the usual manner.

What I claim then is:

1. A knitted glove formed in one continuous piece and having a circularly knit seam- 20 less wrist and hand and fingers integral with

the hand, at least one of the finger strips being seamed on the hand at the base of one side only of such finger or fingers.

25 2. A knitted glove formed in one continuous piece and having a circularly knitted, seamless wrist and hand and fingers integral with the hand, the second and third finger strip being seamed to the hand at the base 30 of one side only of said fingers.

3. A knitted glove formed in one continuous piece and having a circularly knitted, seamless wrist and hand and fingers integral with the hand, the second and third finger 35 strips being formed as integral continuations of the back of the hand and being seamed along their opposite edges and also along their bases at the inside of the hand and the top of the palm.

40 4. A knitted glove formed in one continuous piece and having a circularly knit, seamless wrist and hand and fingers integral with the hand, the second and third fingers being seamed along their opposite edges and across 45 their bases at the inside of the hand and the top of the palm.

5. A knitted glove formed in one continuous piece and having a circularly knitted seamless wrist and hand and fingers integral 50 with the hand, the first and fourth fingers being seamed down their inner edges and the second and third fingers being seamed along their opposite edges and across their bases at the inside of the hand and the top of the palm, the thumb being integral with the hand and seamed along its opposite edges.

6. A knitted glove formed in one continuous piece and having a circularly knit seamless wrist and fingers integral with the 60 hand, each finger being knitted as a flat, oppositely selvaged strip, the finger strips being each of twice the length of the finger and seamed along their opposite edges and also across their bases on one side only.

65 7. A knitted glove formed in one con-

tinuous piece and having a circularly knitted seamless wrist and hand and fingers integral with the hand, each finger being knitted as a flat, oppositely selvaged strip, the finger strips being each of twice the 70 length of the finger and seamed along their opposite edges and also across their bases of one side only, the thumb being formed as a flat oppositely selvaged strip integral with the hand and seamed only along its opposite 75 edges.

8. That method of knitting a glove comprising the following steps: knitting a seamless wrist upon a circular series of needles; then as an integral continuation thereof knitting a seamless hand by circular knitting, and then forming the finger strips as integral continuations of the seamless hand, the finger strips being of twice the length of the finger.

85 9. That method of knitting a glove comprising the following steps: knitting a seamless wrist upon a circular series of needles, then as an integral continuation thereof knitting a seamless hand upon a circular 90 series of needles; forming the first and fourth fingers as flat, oppositely selvaged strips by reciprocating knitting and knitting the second and third finger strips as flat, oppositely selvaged strips by reciprocating 95 knitting, to form finger strips each of double finger length.

10. That method of knitting a glove comprising the following steps; knitting a seamless wrist upon a circular series of needles, then as an integral continuation thereof knitting a seamless hand upon a circular series of needles; forming first and fourth fingers as flat, oppositely selvaged strips by reciprocating 100 knitting to produce strips, and knitting the second and third finger strips as flat, oppositely selvaged strips by reciprocating knitting to form finger strips each of double finger length, and finally seaming the finger strips along their selvaged edges, the tops of the first and fourth fingers and the bases of the second and third fingers at one side of the hand and the upper portion thereof.

11. That method of knitting a glove comprising the following steps: knitting a seamless wrist upon a circular series of needles, then as an integral continuation thereof knitting the lower part of the hand upon a circular series of needles then knitting the thumb as an integral continuation of the 115 hand and as a flat, oppositely selvaged strip of double the thumb length by reciprocating knitting, continuing the knitting of the hand upon the circular series of needles forming the first and fourth fingers as flat, oppositely 120 selvaged strips by reciprocating knitting and knitting the second and third finger strips as flat, oppositely selvaged strips by reciprocating knitting to form two finger strips 125 each of double finger length, and finally 130

seaming the finger strips along their selvaged edges, and along the bases of the second and third fingers at one side of the hand and the upper portion thereof.

- 5 12. That method of knitting a glove comprising the following steps: knitting a seamless wrist upon a circular series of needles, then as an integral continuation thereof knitting the lower part of the hand upon a 16 circular series of needles, then knitting the thumb as an integral continuation of the hand and as a flat, oppositely selvaged strip of double the thumb length by reciprocating knitting, continuing the knitting of the hand 15 upon the circular series of needles, forming the first and fourth fingers as flat, oppo-

sitely selvaged edges by reciprocating knitting, and knitting the second and third finger strips by reciprocating knitting to form two finger strips each of double finger 20 length, and finally seaming the finger strips along their selvaged edges, and along the bases of the second and third fingers and the top of the palm of the hand and the thumb strips along their selvaged edges. 25

In testimony whereof I affix my signature in presence of two witnesses.

GODFREY STIBBE.

Witnesses:
